UNITED STATES PATENT OFFICE.

CHARLES RODNA BECK, OF ANDERSON, INDIANA.

TAKE-UP SPROCKET FOR MOTION-PICTURE MACHINES.

1,125,045.

Specification of Letters Patent.

Patented Jan. 19, 1915.

Application filed October 12, 1911. Serial No. 654,203.

To all whom it may concern:

Be it known that I, CHARLES RODNA BECK, a citizen of the United States, residing at Anderson, in the county of Madison and State of Indiana, have invented certain new and useful Improvements in Take-Up Sprockets for Motion-Picture Machines, of which the following is a specification.

This invention relates to improvements in motion picture machines, and particularly to a sprocket for guiding the film in front of the shutter.

One object of the invention is to provide a film feeding and take-up sprocket whereby the liability of the film breaking is reduced to a minimum.

Other objects and advantages will be apparent from the following description and with particular reference to the accompanying drawings.

In the drawings: Figure 1 is an enlarged longitudinal sectional view of one of the feeding and take-up sprockets for the film, and Fig. 2 is an end view thereof.

Referring particularly to the drawings, 10 represents a shaft suitably driven by the usual train of gears. (Not shown.) Mounted on the shaft 10, is a sleeve 11, having formed on each end thereof a reduced portion 12. On the reduced portions 12 at each end of the sleeve 11 are arranged the sprockets 13 which are provided with spurs or teeth 14 for engagement with the openings at the edges of the film. This sleeve 11 is secured on the shaft 10 by the screw 15 and rotates therewith. Each of the sprockets is provided with a recess 16 in which is secured a spring pawl 17. The pawls 17 engage with the free ends of the teeth of the ratchet wheels 18 which are secured to the

reduced portions 12 by the screws 18' and rotatable with the sleeve 11 so that when the shaft 10 rotates the ratchets and pawls will be in engagement to drive the sprockets 13 to feed the film forward. Should the film loop become straightened out the sprockets 13 would rotate faster than the shaft 10, thus avoiding any strong pull between the feed sprockets and the usual intermittent sprockets (not shown) thus preventing any great strain on the film which might result in tearing or breaking the same.

From the foregoing it will readily be seen that while the movement of the film is positive, still should the tension on the film become increased the sprockets would slip on the shaft at a speed greater than that of the shaft, so that the operator could, while still turning the crank, reach in the machine 60 and pull the loops out.

What is claimed is:

In a device of the kind described, a shaft having a sleeve thereon, a sprocket wheel mounted at each end of said sleeve, a ratchet member rotatably mounted on each end of the sleeve outside of said sprockets, means to lock said ratchet member on the sleeve whereby the ratchet member may be adjusted around the sleeve and held in adjusted position, said ratchet member when so adjusted serving as a collar for the sprocket, a pawl carried by each sprocket and engaging a respective ratchet member.

In testimony whereof I affix my signature, 75 in the presence of two witnesses.

CHARLES RODNA BECK.
